RAPID TRANSIT CAR

Richard L. Lich, St. Louis, Mo., assignor to General Steel Industries, Inc., Granite City, Ill., a corporation of Delaware

Filed Oct. 8, 1962, Ser. No. 72,008

Term of patent 7 years

(Cl. D66—1)

FIG. 1 is a top view of a rapid transit car showing my new design.

FIG. 2 is a side view of the car.

FIG. 3 is a rear end view of the car.

FIG. 4 is a front end view of the car.

The undisclosed side of the car is substantially the same in appearance as the side shown.

I claim:

The ornamental design for a rapid transit car, substantially as shown and described.
